(57) **CLAIM**

The ornamental design for a coating machine as shown and described.

DESCRIPTION

FIG. 1 is a perspective front view of a coating machine showing our new design;

FIG. 2 is an alternative perspective front view thereof;

FIG. 3 is a front view thereof;

FIG. 4 is a rear view thereof;

FIG. 5 is a perspective rear view thereof;

FIG. 6 is a right side view thereof;

FIG. 7 is a left side view thereof;

FIG. 8 is a top plan view thereof;

FIG. 9 is a bottom view thereof;

FIG. 10 is a perspective front view with a chamber door in an open in-use position thereof; and

FIG. 11 is an alternative perspective front view with the chamber door in an open in-use position thereof.

The broken lines shown in FIG. 9 illustrate environmental structure and form no part of the claimed design.
